UNITED STATES PATENT OFFICE

2,530,473

SWITCH HEATER

William A. Lebus, Chicago, Ill., assignor to The
Protectoseal Company, Chicago, Ill., a corpora-
tion of Illinois

Application October 22, 1948, Serial No. 55,877

2 Claims. (Cl. 158—94)

1

This invention relates to railway switch heaters, a novel burner assembly for heating switches during extreme cold weather to prevent the accumulation of ice about the switches, and among its objects is to provide a novel burner assembly employing a wick, wherein the wick may be readily advanced through the wick tube when its protruding end has been burned off.

Another object is to provide a fuel tank with a stationary connecting member welded or otherwise secured to a wall of the tank around an opening therein, which connecting member cooperates with the burner assembly to lock the latter to the stationary connecting member but permitting manipulation of the burner assembly whereby it may be readily detached from the connecting member so as to obtain access to the wick at a point below the burner assembly, whereby the end of the wick may be readily pushed above the wick tube to present an unburned part of the wick in position to be ignited.

Another object is to provide a switch heater of novel construction which may be employed at switch points of railway tracks and at the switches themselves to prevent the accumulation of ice about the switch points and switches.

Another object is to provide a filler opening in a wall of the tank closed by a hinged lid which may be readily swung into open position by the nozzle of an oil can thereby permitting fuel oil to be poured into the tank.

With these and other objects and advantages in view, this invention consists in several novel features of construction, arrangement and combination of parts hereinafter fully set forth and more particularly defined in the appended claims.

The invention is clearly illustrated in the drawings accompanying the specification, in which:

Fig. 1 is a plan of a switch heater embodying a simple form of the present invention showing the same as lying down.

Fig. 2 is a side elevation thereof partly broken out.

Fig. 3 is an enlarged central vertical section through the burner assembly and showing its connection with a fragment of the tank.

Fig. 4 is a horizontal section taken on the line 4—4 of Fig. 3, and

Fig. 5 is an end elevation of the switch heater looking in the direction of the arrow 5 in Fig. 2.

Referring to said drawings, the reference character 6 designates a fuel tank for containing kerosene or other suitable fuel oil. As shown, the fuel tank is of elongated form with its wall

7 somewhat of oval form in cross section, and closed at its ends by heads 8 welded or otherwise secured thereto by suitable leak-proof means.

In that part of the wall 7 which forms the top 10 of the tank when lying down as seen in Figs. 1 and 2, is an opening 9 located adjacent one end of the tank, and surrounding said opening is a stationary annular connecting member 10 which is welded to the tank wall. The connecting member is here shown as formed with an annular flange 11 at its lower edge that is spot welded to the wall 7 of the tank.

The burner assembly indicated generally by the reference character 12, is provided with a connecting member 13 which is rotatable with respect to the stationary connecting member 10 and is provided with locking means cooperating with the stationary connecting member to lock the burner assembly to the tank but so arranged that upon slight rotation of the burner assembly it may be detached from the tank.

The means shown for accomplishing this result comprises an internally extending flange 14 on the stationary connecting member, having notches 14a and provided with an annular down-turned rim 15 through which the notches 14a are extended. The rotatable connecting member 13 is provided with radially extending tongues 16 which pass through the notches 14a and engage under the rim 15 of the flange 14 when the burner assembly is partially rotated. To remove the burner assembly, it is rotated until the tongues register with the notches, whereupon it may be raised and detached from the stationary connecting member.

As shown the burner assembly is provided with a cap 17 of stepped formation, the annular top wall 18 of which carries the rotatable connecting member 13. From the outer edge of the top wall 18 depends a vertical ring-like wall 19, which terminates in a horizontal annular wall 20 that seats upon the flange 14 of the stationary connecting member and from the outer edge of said horizontal wall 20 depends a ring-like wall 21 which fits around the side wall of the stationary connecting member, and from the lower edge of said annular upright wall 21 extends a horizontal annular wall 22, from the outer edge of which depends a vertical ring-like wall 23. A chimney 24 is welded or otherwise rigidly secured to the upright wall 23 of the cap 17 and is preferably provided with air apertures 25 adjacent its lower edge.

A wick tube, shown at 26, is supported by the cap 17 and it is here shown as formed with an

annular outer bead or outward indentations 27 which rest upon the top wall 18 of the cap. The rotatable connecting member 13 is shown as welded to the wick tube with the top wall 18 of the cap tightly gripped between the bead or indentations 27 and rotatable connecting member.

The wick 28 extends down from the wick tube into the fuel in the fuel tank with its upper end protruding from the upper end of the wick tube, whereby when ignited the wick will burn until the burned part thereof reaches the wick tube. If desired, one or more inwardly bent upwardly direct tongues 30 may be formed in the wall of the wick tube to engage with the wick and prevent any possibility of the wick falling down from the wick tube.

A flanged hood 31 which may act as a snuffer is removably supported on a flanged guide member 32 welded to the top wall of the tank. The flange of the hood is held in the grooves between the body of the guide member and its flanges. When it is desired to use this hood as a snuffer, it is slid out of the guide member and placed upon the cap as seen in Fig. 2.

A filler opening 33 surrounded by a rim 33a, is provided in the wall of the tank at the end thereof, opposite the burner assembly, and a lid 34 hingedly connected to ears 35 which are welded or otherwise secured to the wall of the tank is provided for closing the filler opening 33. The lid is formed with an upwardly inclined lip 36 at the end opposite its hinged end to facilitate lifting the lid. A weighted block 34a is welded or otherwise secured to the lid to aid in keeping it closed. An attendant wishing to supply the tank with kerosene or other fuel oil thrusts the end of the nozzle of the oil can underneath the lip 36 thereby raising the lid and enabling the nozzle to be thrust into the filler opening. When the nozzle is withdrawn, the lid drops by gravity and closes the filler opening.

A handle 37 welded or otherwise secured to the head 8 adjacent the filler opening provides convenient means whereby the switch heater may be carried about.

In use, the switch heaters are placed under switch points of railway tracks or under the switches, and the wicks ignited. The heat from the burning fuel serves to prevent the accumulation of ice around the switch points and switches where the devices are used. They may also be used as road flares.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire and secure by Letters Patent is:

1. In a liquid fuel burning heater, a fuel tank having an opening in its wall, a stationary, tubular member rigidly secured to said tank and encircling the opening therein, the outer end of said member terminating in an internal flange, a cap of greater diameter than said member having an inner, an outer, and an intermediate offset therein to form a concentric stepped structure, the intermediate offset of which is of a size to set on said tubular member, a tubular chimney connected at its lower end to and carried by said outer offset, said chimney having a plurality of openings therein adjacent said lower end for the passage of air therethrough, a wick tube extending through and carried by the central portion of said cap, a wick member positioned in said tank and extending through said tube, a locking member rigidly carried by said cap and extending inwardly therefrom into said tubular member, and co-operating means on said locking member and the flange on said tubular member for detachably locking said cap to said tubular member.
2. In a liquid fuel burning heater, a fuel tank having an opening in its wall, a stationary, tubular member rigidly secured to said tank and encircling the opening therein, the outer end of said member terminating in an internal flange, a cap of greater diameter than said member having an inner, an outer, and an intermediate offset therein to form a concentric, stepped structure, the intermediate offset of which is of a size to set on said tubular member, a tubular chimney connected at its lower end to and carried by said outer offset, said chimney having a plurality of openings therein adjacent said lower end for the passage of air therethrough, a wick tube extending through and carried by the central portion of said cap, a wick member positioned in said tank and extending through said tube, a cover for said wick adapted to engage the inner offset, a locking member rigidly carried by said cap and extending inwardly therefrom into said tubular member, and a plurality of radially extending tongues carried by said locking member engageable with portions of the flange on said tubular member for detachably locking said cap to said tubular member.
